(57) CLAIM

The ornamental design for a combination ceiling fan motor housing light kit, as shown and described.

DESCRIPTION

FIG. 1 is a top perspective view of a combination ceiling fan motor housing and light kit, showing my new design; FIG. 2 is a bottom perspective view thereof;

FIG. 3 is a top view thereof;

FIG. 4 is a bottom view thereof;

FIG. 5 is a front view thereof;

FIG. 6 is a left-side view thereof;

FIG. 7 is rear view thereof; and,

FIG. 8 is a right-side view thereof.

The broken lines illustrate environmental structure and portions of the ceiling fan motor housing and light kit. None of the broken lines form part of the claimed design.

1 Claim, 6 Drawing Sheets
